MERCURY SWITCH

Karl Hunciker, Chicago, Ill., assignor to Ira E. McCabe, Chicago, Ill.

Application April 12, 1933, Serial No. 665,628

5 Claims. (Cl. 200—112)

This invention relates to improvements in mercury switches and more particularly to that type of mercury switch in which the tube and contained mercury remains stationary and movement is imparted to elements also contained within the tube to make and break the circuit therein.

The mercury tube switch comprising a sealed tube or envelope, usually of glass, containing a movable body of mercury and an inert gas having spaced apart electrodes sealed in the walls and entering the interior so that upon tilting the mercury is caused to flow from end to end to close and open the circuit between the electrodes is a commercial product well known in the switch art.

It is an object of this invention to produce a switch of this general character which requires but a small amount of mercury and in which the tube and mercury remain stationary while one or more of the electrodes are caused to move into and out of contact with the mercury to make and break the circuit therein, thereby not only making a saving in the cost of the mercury employed but also obviating the internal stresses and strains upon the tube heretofore caused by the mercury hammer in the tilting tube type.

It is also an object of this invention to actuate one or more of the electrodes by magnetic force, thereby obviating the necessity of a mechanical snap movement heretofore used in the rapid tilting of the tube to throw the mercury from one position to another, and allow mercury tube switches to be employed under conditions where snap action switches would be impracticable.

With these and other objects in view reference is made to the accompanying sheet of drawings which illustrates preferred embodiments of this invention with the understanding that minor detail changes may be made therein without departing from the scope thereof.

In the drawing—

Figure 1 is a vertical central sectional view, with parts shown in front elevation, of one form of this invention.

Figure 2 is a view partly in side elevation and partly in central vertical section of Figure 1.

Figure 3 is a view similar to Figure 1 of a modification.

Figure 4 is a view similar to Figure 2 of Figure 3.

Figure 5 is a view similar to Figure 1 of another modification.

Figure 6 is a view similar to Figure 1 of a further modification.

Figure 7 is a view similar to Figure 1 of a still further modification.

Figure 8 is a view similar to Figure 1 of a different form of this invention illustrating in front elevation the actuating means thereof.

Figure 9 is a view similar to Figure 1 of another modification.

Figure 10 is a detail view in side elevation of Figure 9, with the tube removed.

In all the embodiments of this invention as illustrated the switch includes a cylindrical glass envelope or tube 1, closed at the lower end preferably to form a depending pocket or cup 2 adapted to receive and retain a small body of mercury or other fluid electrical conductor 3. The upper end is preferably closed by a pinch seal which embraces and seals in the body thereof one or more leading-in wires 4 and a filling stem 5 through which the gas is substituted for the contained air, mercury inserted and the stem then tipped off. The leading-in wires are of such character as to seal readily in the body of the envelope and extend a sufficient distance beyond the exterior of the sealed end for the ready attachment of the circuit wires, not shown. Electrodes extending within the tube 1 are welded or otherwise secured to the inner ends of the leading-in wires.

In Figures 1 and 2, one electrode 6 is in the form of a rigid wire which extends from its leading-in wire to engage the mercury 3 in the cup 2 and is terminated below the surface thereof. The other electrode 7 is preferably flattened, as shown in Figure 2, and corrugated or fluted adjacent its leading-in wire as at 8 to increase its flexibility and resiliency and then extended over the mercury 3 and terminated in a bent down end 9 normally out of contact with the mercury 3, so formed that the bend is normally spaced a lesser distance from the tube 1 than the distance of the extremity 9 from the mercury 3. That part of the electrode between the corrugation 8 and extension which passes over the mercury 3 supports a preferably semi-cylindrical section or member 10 of magnetic metal spaced apart from the wall of the tube 1 and adapted to respond as an armature when affected by the field of a magnet, such as the fixed magnet 11 shown in Figure 1, so that when a magnet is brought sufficiently close to the tube 1 the armature is caused to move toward it flexing the portion 8 of the electrode 7 until the armature 10 contacts the wall of the tube and such movement causes the end 9 of the electrode 7 to contact and enter the mercury 3, thereby closing the circuit through the switch. When the magnet is moved away from the tube 1, the pull on the

armature 10 is released and the electrode 7 straightens out to remove the end 9 from the mercury and thereby break the circuit.

While a fixed magnet is shown by way of example, an electro-magnet may be employed which may be stationary, if desired, with means to energize it when it is desired to close the circuit. When it is desired to use a fixed magnet, such as 11, any desired means may be employed to reciprocate it toward and away from the tube 1.

In the form shown in Figures 3 and 4, one electrode 7a is corrugated or fluted to provide resilient flexibility, and supports a magnetic member 10, in the same manner as shown in Figures 1 and 2, 15 however, the portion extending over the mercury passes through an insulating material yoke 12 before terminating in the bent down end 9 normally out of contact with the mercury 3. The other electrode 13 is also preferably flattened and corrugated or fluted at 8a adjacent its leading-in wire to provide resilient flexibility then terminates in a round portion passing through the yoke 12 spaced apart from the other electrode and ends in a portion 14 parallel to the end 9 of the 20 other and also normally out of contact with the mercury 3.

In this form when the armature is actuated by a magnet to move in the direction of the adjacent wall of the tube 1 both ends 9 and 14 are, by 30 means of the yoke 12, brought into contact with the mercury 3 to close the circuit therethrough and when the magnetic force is removed the armature 10 is released and the corrugated or fluted portions 8 and 8a straighten out, removing 35 the ends 9 and 14 from the mercury to break the circuit.

In the form shown in Figure 5, one leading-in wire 4 passes through the pinch seal and another 40 4a is sealed in the wall of the pocket 2 to which is welded or otherwise secured a short electrode 15 which is always submerged in the mercury 3, the other electrode 7b is welded or otherwise secured to the leading-in wire 4, is corrugated or fluted, as at 8, adjacent thereto to provide resiliency and supports a magnetic member 10 in the same manner as shown in Figure 1. In this form the electrode 7b terminates in an end 16 which normally contacts the mercury 3 and enters below the surface thereof, thereby completing the circuit through the switch.

When a magnetic force is applied to draw the armature 10 toward the adjacent wall of the tube 1, the end 16 of the electrode 7b is withdrawn out of contact with the mercury to break the circuit, as shown in Figure 5.

In the form illustrated in Figure 6, the electrode 7b is constructed in the manner shown in Figure 5 with the end 16 normally in contact with the mercury 3 and the electrode 13 constructed 60 in the manner shown in Figure 3 with the end 14 normally out of contact with the mercury 3, the two ends 14 and 16 passing through the yoke 12 holding them in spaced relation and when the armature 10 is drawn toward the adjacent wall 65 of the tube 1, the end 16 is moved out of contact with the mercury 3 and through the yoke 12 the end 14 is moved into contact with the said mercury. Since the electrode 15 of the leading-in wire 4a is always in contact with the mercury 3, a circuit is always closed through the switch from the electrode 15 through either electrode 7b or electrode 13, depending upon the actuation of the armature 10.

Figure 7 illustrates a modification in which the 75 electrodes 7c and 13a are both flattened to pro-

duce resilient flexibility and the electrode 7c is preferably provided with one corrugation or fluted portion 8b to add to its flexibility, otherwise, they are both of the same construction as shown in Figures 3 and 4 with the ends passing through 5 the yoke 12 and both normally out of contact with the mercury 3. In this form the leading-in wire 4a is sealed in the walls of the pocket 2 and supports the electrode 15 always submerged in the mercury 3, so that when the circuit is closed 10 the current flowing from electrode 15 divides and passes through the electrodes 7c and 13a.

Figure 8 illustrates another form of this general type of switch illustrating the application of this principle to two actuating means. In this instance, the electrode 7b is constructed in the same manner as shown in Figure 5 and the electrode 13b is corrugated or provided with a fluted portion 8a to provide resilient flexibility and therebelow supports a magnetic member 10a similar to the member 10, and the end 17 is bent to normally terminate above and out of contact with the mercury 3, as shown in full lines. Under normal conditions, that is when the switch is removed from the influence of an electromagnetic 25 field, and the armature 10a attracted by the magnet 11, the electrode 7b will through its end 16 contact the mercury 3, while the end 17 of the other electrode 13a will be out of contact with the mercury so that the circuit is broken within 30 the tube 1.

This switch is of particular use where one magnet 11 will normally operate to open and close the circuit through the switch and another magnet 11a, such as an electro-magnet, may be employed, when energized to open the circuit when closed by the magnet 11 by withdrawing the end 16 out of the mercury. An example of such use may be found in a control system for an electrically operated and controlled fluid fuel burner 40 mechanism when the magnet 11 may be reciprocated to close and open the burner motor circuit, or a control circuit thereof, by a room thermostat and the other magnet 11a being an electro-magnet, as shown, may be connected in a circuit containing a commercial boiler control responsive to interior conditions of the boiler which circuit is normally open in the boiler control but which is caused to close upon excessive temperature or pressure within the boiler. The energization of 45 the magnet 11a will draw the armature 10 towards the adjacent wall of the tube 1 and withdraw the end 16 of the electrode 7b from the mercury 3 and maintain it out of contact irrespective of the position of the magnet 11 until the conditions 55 within the boiler become normal and the circuit again opened within the boiler control.

In the form illustrated in Figure 9, one electrode 6 is similar to the one shown in Figure 1, and terminates below the surface of the mercury 60 3 while the other is so formed to support the armature 10 independently of the resilient flexible portion. In order to accomplish this, the electrode 7d is provided with an offset 7c between its leading-in wire 4 and the flattened 65 and corrugated or fluted portion 8 formed to normally maintain its end 18 out of contact with the mercury 3. The upper portion of the armature 10 is provided with ears 10a pivotally mounted upon a vertical support 19 depending 70 from the offset 7c and the lower portion with a forked extension 10b, as shown, adapted to embrace the end 18 of the electrode and normally hold the armature 10 against the end 20 of the support 19, whereby the weight of the armature 75

acts as a stabilizer in the event of vibration of the switch mounting.

There have been many types of magnetic tubes used such as disclosed by the Hatfield Patent No. 1,094,440 and the Hewitt Patent No. 1,110,548 wherein the armature is used to bridge two pools of mercury or as disclosed in the Keyes Patent No. 1,461,038 and the Phelan et al. Patent No. 1,558,277, wherein the armature is pivoted and swung.

These latter types offer difficulties in that the current must be carried between the bearings and arcing occurs causing unsatisfactory and unreliable performance since the surface which must act as a pivot may become pitted, welded or otherwise deformed or defaced as to make unsatisfactory contact or an unsatisfactory bearing.

This invention overcomes the weakness and difficulties of the prior art and will perform the requirements of such a switch satisfactorily.

It is also possible with this type of construction, as evident in Figure 1, to insure the opening of the circuit through the switch upon failure of the magnetic field or failure of the magnet operating mechanism, and further the flexible armature carrying electrode may be made resilient enough to prevent its movement by gravity, to make or break contact with the mercury, should the switch be tilted out of vertical position when not under the influence of the magnetic field. As the body of mercury is small and well contained in the cup and with its natural tendency to adhere to the glass it requires considerable rotation of the switch to shift the position of the mercury so that, except in extreme cases, rotation from the vertical will not effect a make or break in the switch.

When the switch is mounted as to be subjected to shocks or vibrations the construction must be such that the movable electrode is not caused to flutter in and out of contact with the mercury pool and cause a succession of make and breaks.

Figure 1 illustrates one method to prevent such operation. In this instance, the movable electrode is formed—at its extremity which contacts the mercury—so that it rests against the inner wall of the tube when the switch circuit is open or else is so positioned that the distance from the electrode to the glass is less than that from the electrode to the mercury so that the amplitude of movement is confined to that of the shorter distance.

Figure 9 illustrates another method by supporting the armature independently of the flexible electrode and causing the movement of the armature to flex the electrode, the armature is provided with a forked extension through which the movable electrode passes and the weight of the armature acts as a stabilizer to prevent vibrations of the electrode during those periods in which the circuit is desired open. When constructed in the manner shown, the armature is not used as a conductor and the possibility of arcing or unsatisfactory bearing is thereby eliminated.

What I claim is:

1. An electric switch comprising a sealed container, a body of electric conducting fluid therein, an integral flexible wire electrode having one end free and normally out of contact with said fluid, a second integral electrode adapted to make contact with said fluid, a rectangular curved armature secured at the crown of curvature upon said first electrode intermediate its length and spaced apart from its free end, in combination with means exterior of said container to actuate said flexible electrode to close the circuit through said fluid including a magnet adapted to include said armature within the magnetic field thereof. 15

2. An electric switch including an elongated cylindrical vertical sealed container, a body of conducting fluid in the bottom thereof, two electrodes sealed in the upper end thereof, one entering the said body of conducting fluid and the other fluted and flexible throughout the upper portion thereof and terminated out of contact with said conducting fluid, a rectangular armature having curved sides parallel to said container wall secured upon said electrode below the fluted portion and above the free end thereof adapted to be flexed by a magnetic field exterior of the container to submerge the end of said electrode within said conducting fluid. 20 25

3. An electric switch comprising a sealed container, a body of electrical conducting fluid therein, a wire electrode including a flexible portion having one end free and normally out of contact with said fluid, a second electrode adapted to make contact with said fluid, a rectangular curved armature mounted upon said first electrode intermediate its length and spaced apart from its free end, in combination with a magnet adapted to include said armature within the magnetic field thereof to flex said first electrode and cause its free end to make contact with said fluid. 30 35 40

4. An electric switch comprising a sealed container, a body of electrical conducting fluid therein, an electrode including a flexible portion having one end free and normally out of contact with said fluid, a second electrode adapted to make contact with said fluid, a pivoted curved armature within the container in engagement with the free end of the first electrode, in combination with a magnet adapted to include said armature within the magnetic field thereof to flex said first electrode and cause its free end to make contact with said fluid. 45 50 55

5. The structure of claim 4, wherein the upper portion of said armature is pivoted intermediate a support therefor extending from the non-flexible portion of said first electrode, and the lower portion is extended to form a fork embracing the free end of said electrode to normally hold the armature in contact with the free end of said support to stabilize vibration of the free end of said electrode. 60 65
